CLAIM

The ornamental design for a photocuring device, as shown and described.

DESCRIPTION

FIG. 1 is a front, top, right perspective view of a photocuring device, showing our new design;

FIG. 2 is a front elevational view thereof; and
FIG. 3 is a rear elevational view thereof.

FIG. 4 is a left side elevational view thereof;

FIG. 5 is a right side elevational view thereof;

FIG. 6 is a top plan view thereof; and,

FIG. 7 is a perspective view thereof, shown in an environment of use.

In the drawings, the evenly spaced dash-dash broken lines illustrate portions of the photocuring device which form no part of the claimed design. The dot-dot broken lines illustrate environmental subject matter which forms no part of the claimed design. The dot-dash broken lines illustrate a boundary to the claimed design and form no part thereof.

1 Claim, 7 Drawing Sheets
